COMBINATION GAS AND OIL BURNER AND
CONTROL SYSTEM THEREFOR

Richard H. Siemon, Kansas City, Mo.

Application October 11, 1948, Serial No. 53,951

10 Claims. (Cl. 158—11)

1

This invention relates to new and useful improvements in automatically controlled combination gas and oil burners, and relates particularly to a burner adapted to burn either gas or oil, and to switch automatically from one fuel to the other responsively to certain control conditions, such as the outdoor atmospheric temperature or the pressure in the gas supply line.

Due to the shortage of fuel gas for heating prevailing in many parts of the country, numerous cities have conditioned permits to install household gas heating equipment on the provision of a stand-by fuel supply such as oil, said oil to be burned during the periods of peak gas load. It is therefore the principal object of this invention to provide a combination gas and oil burner arrangement adapted to burn gas as long as the outside air remains above a predetermined temperature, but which will switch automatically to oil whenever the outside air falls below said predetermined temperature, and to switch automatically back to gas when the outside temperature again rises above said predetermined level. Since the gas load in a gas supply system is generally inversely proportional to the outside temperature, this control means is effective to turn off the gas during peak load periods.

Another object is the provision, in a device of the character described, of automatic pressure sensitive means for switching from gas to oil fuel whenever the pressure in the gas supply line falls below a predetermined level, regardless of the outside temperature.

A further object is the provision of a combination gas and oil burner system wherein the oil is ignited by means actuated by an inside thermostat, and having means actuated by the oil flame to ignite the gas fuel and to shut off the oil burner whenever the outside temperature and the gas pressure are above predetermined levels, and automatic means for switching to oil fuel whenever either the outside temperature or the gas pressure falls below said predetermined levels.

A still further object is the provision, in a combination gas and oil burner system of the character described, of independent draft means for supplying air for combustion to said gas and oil burners, the draft means for said gas burner being self-regulating according to the amount of gas being burned, and being adapted to close automatically when oil is being burned.

Other objects are simplicity and economy of construction, accuracy and dependability of op-

2

eration, adaptability to include a standard gun-type oil burner, and adaptability to use only standard, commercially available control devices.

5 With these objects in view as well as other objects which will appear in the course of the specification, reference will be had to the drawings, wherein:

Figure 1 is a schematic layout of an automatically controlled combination gas and oil burner system embodying the present invention.

Fig. 2 is an enlarged fragmentary section taken on line II—II of Fig. 1, with parts left in elevation.

15 Fig. 3 is a fragmentary section taken on line III—III of Fig. 2, with parts left in elevation.

Fig. 4 is a fragmentary section taken on line IV—IV of Fig. 2, with parts broken away and other parts left in plan.

20 Fig. 5 is a fragmentary section taken on line V—V of Fig. 4, with parts broken away and other parts omitted.

Fig. 6 is a fragmentary section taken on line VI—VI of Fig. 5.

25 Fig. 7 is a fragmentary section taken on line VII—VII of Fig. 2.

Fig. 8 is a schematic wiring diagram of the burner controls.

Fig. 9 is a schematic wiring diagram of a modified form of the burner control system.

Fig. 10 is a view similar to Fig. 4, including the principal modifications indicated in Fig. 9.

Like reference numerals apply to similar parts throughout the several views, and the numeral 35 2 applies to a furnace shown in Fig. 1 disposed in the basement of a building having an outside wall 4 and a floor partition 6. Said furnace may be of any common type such as warm air, hot water, or steam, and is provided with a suitable stack pipe 8. The combination gas and oil burner includes a standard gun-type oil burner 10, said oil burner including a blast tube 12 disposed horizontally, said blast tube extending at its inner end flush with the inner surface 40 of the refractory combustion chamber wall 14 of furnace 2, a fan housing 16 carried by and interconnected with said blast tube adjacent the outer end thereof, a fan wheel 18 carried in said housing and operable by a motor 20 mounted at one side of the fan housing to supply air under forced draft to blast tube 12, and an oil pump 22 mounted on the opposite side of fan housing 16 coaxially with motor 20, said pump also being driven by said motor through 45 coupling 24, as shown in Fig. 3. Said pump is

50 55

provided with a suction line 26 and a return line 28 connecting it with a suitable supply of fuel oil. The delivery line 30 of said pump is interconnected with an oil tube 32 which passes through rear closure plate 34 of blast tube 12 and extends axially through said blast tube to a point adjacent the open inner end thereof. Said oil tube carries at its inner end a nozzle 36 adapted to direct a finely divided oil spray into the furnace combustion chamber. Said oil tube is supported intermediate its ends within blast tube 12 by means of spider 38, and the outer end portion of blast tube 12 is supported by a floor-engaging leg 40.

Oil emerging from nozzle 36 is ignited by an electric spark passing across spark gap 42 between electrodes 44 adjacent the tip of said nozzle. Said electrodes are disposed adjacent oil tube 32, and are supported from said oil tube by clamp 46. The electric leads 48 and 50 to said electrodes pass through insulating fittings 52 provided therefore in closure plate 34, and are respectively interconnected with the secondary terminals of ignition transformer 54, which is carried in a suitable housing mounted on fan housing 16.

As best shown in Figs. 2, 3 and 7, a burner box 56 of sheet metal construction is disposed about the inner end portion of blast tube 12. Said box is substantially rectangular in transverse cross-section, and comprises a top wall 58, bottom wall 60, side walls 62 and 64, an outer end wall 66, and an inner end wall 68 flush with the inner surface of furnace wall 14 and extending from the upper edge of box 56 to a point spaced apart from the lower edge thereof, as best shown in Fig. 5. An open-ended tube 70 extends horizontally between outer wall 66 and inner wall 68 through the upper portion of box 56, and blast tube 12 of the oil burner extends therethrough. The space between tube 70 and blast tube 12 is filled with a heat insulating material 72.

A plurality of horizontally disposed, laterally spaced apart gas burner tubes 74 are carried in the lower portion of burner box 56 parallel to blast tube 12, being secured rigidly to brackets 76 extending between and fixed to side walls 62 and 64. The open inner ends of said gas burner tubes are flush with the inner surface of furnace wall 14 and beneath the lower edge of inner wall 68, and the outer ends of said tubes are fitted with apertured plates 78 which serve to center therein coaxially disposed pipe nipples 80, to the inner ends of which are carried nozzles 82, so disposed that when gas is supplied to said nozzles through said nipples, air will be drawn into tubes 74 through apertured plates 78 and intermixed with said gas. Pipe nipples 80 are externally threaded to receive thereon closure discs 84, which may be moved adjustably to and from the ends of tubes 74 to regulate the amount of air entering said tubes. All air which does not enter tubes 74 will pass around the outside of said tubes and be intermixed with the burning air-gas mixture emerging from the inner ends of said tubes, thereby providing a secondary supply of air for complete combustion. The outer ends of nipples 80 are interconnected with a common transverse header pipe 86. Said header is mounted on a bracket 88 fixed to bottom 60 of box 56, extends outwardly through side wall 64 of said box, and is interconnected at its outer end with a gas supply pipe 90.

The lower portion of burner box 56 is extended outwardly from the upper portion thereof, and is

provided at its outer end with a damper door 92 hinged at 94, and adapted normally to be retained closed by gravity. Said damper is operated by a pressure sensitive damper control 96 disposed in gas supply line 98. As best shown in Fig. 6, said damper control comprises a housing 98 carrying a flexible diaphragm 100 beneath which gas from pipe 98 is adapted to enter. A lever 102 is pivoted adjacent one end to housing 98 at 104, and is pivotally connected at 106 intermediate its ends to a slide rod 108 fixed to and operable by diaphragm 100. The free end of lever 102 is connected by chain 110 with a pin 112 fixed to the free edge of damper door 92. Thus whenever there is gas pressure in gas supply line 98, the damper will be opened, and the amount it is opened will be proportional to the gas pressure. Hence the damper is automatically regulated and by selecting a damper control of the proper sensitivity, and by adjusting the length of chain 110, damper 92 will open sufficiently to permit the amount of air required for proper combustion of the gas being burned.

A solenoid operated gas valve 114 is inserted in gas supply line 98 behind damper control 96, and a pilot gas tube 116 is interconnected with said supply line behind said main valve, said connection usually being made within the body of valve 114 itself. Said pilot tube is provided with a solenoid operated valve 118, enters burner box 56 immediately beneath header 86, and extends transversely beneath the inner ends of gas burner tubes 74. That portion of said pilot tube adjacent the forward ends of the gas burner tubes is provided with a plurality of longitudinally spaced apertures 120. The gas escaping from said apertures is ignited by the flame of the oil burner as hereinafter described.

Within burner box 56, pilot tube 116 is provided with a branch tube 122 adapted to supply gas to a flame actuated switch device 124 best shown in Figs. 5 and 8. Said device is disposed in the upper portion of burner box 56 adjacent tube 70, and comprises a tube 125 fixed in outer wall 66 of said burner box and extending to a point adjacent the inner wall 68 thereof, a horseshoe shaped bimetallic element 126 fixed at one end to the inner end of said tube and fixed at its opposite end to one end of a rod 128 disposed within tube 125, and an electric switch 130 carried in a housing 132 disposed outside of burner box 56 and operable by the movement of rod 128. As shown in Fig. 5, tube 122 supplies gas to a jet 134 adapted to apply a flame against bimetallic element 126. Switch 130 remains open so long as no flame is applied to the bimetallic element, but closes when the flame is so applied. Inner wall 68 of burner box 56 is provided with an aperture 136 adjacent bimetallic element 126, and gas supplied to jet 134 may be ignited directly through said aperture by the oil burner flame. However, in order to insure positive ignition of the jet, an auxiliary pilot tube 138 is interconnected at its lower end with pilot tube 116 and extends upwardly adjacent wall 68 and across aperture 136. Said auxiliary pilot tube is provided along its length with spaced apart holes 140 as shown in Fig. 5. This device is known as a "ladder pilot." When gas from pilot tube 116 is ignited by the oil burner, gas escaping from the lower holes 140 of tube 138 is ignited by said pilot. The flame then travels upwardly along tube 138, successively lighting gas from the next higher hole 140 until a flame is directed inwardly through aperture 136 to ignite jet 134.

Referring to Fig. 8 for a wiring diagram of the control system, it will be seen that line wires 142 and 144 are connected by wires 146 and 148 with the primary terminals of a transformer 150 suitable for stepping the line voltage down to a level suitable for the operation of relays, etc. A main switch 152 is disposed in wires 146 and 148, and a limit control 154 is disposed in series in wire 148. Said limit control comprises an electrical switch normally closed and adapted to be opened by a bimetallic element 156 whenever said element is heated above a predetermined temperature. Said bimetallic element is positioned in the furnace bonnet as indicated in Fig. 1, and thus adapts the limit control to shut off the entire system whenever the bonnet temperature exceeds a safe level.

Wire 148 is connected by wire 158 with the armature of a relay 160, and the fixed terminal of said relay is connected by wire 162 with oil burner motor 20, and by means of wires 162 and 164 with one of the primary terminals of ignition transformer 54. The other primary terminal of said transformer, and the other terminal of said motor 20 are connected with wire 146 by wires 166 and wire 168, thus completing the oil burner circuit. Relay 160 is normally open, and hence the oil burner can not function except when the coil of relay 160 is energized. One of the secondary terminals of transformer 54 is connected to said relay coil by wire 170, and the other wire 172 from said coil is connected with the armature of normally open relay 174. The other secondary terminal of transformer 150 is connected by wire 176 with a movable switch member of stack switch 178. Said movable switch member is operable by a bimetallic member 180 disposed in the stack pipe 8 of the furnace 2 to connect wire 176 with either a wire 182 connected with the armature of relay 174, when bimetallic member 180 is heated, or with a wire 184. Wire 184 is connected with a safety switch comprising in series a heater coil 186, a bimetallic switch element 188 adapted to be heated by said heater coil, and a fixed contact 190 connected with wire 182 by wire 191. Said safety switch is normally closed when heater coil 186 is not energized. Hence when relay 174 is closed by means hereinafter described, the secondary circuit of transformer 150 is closed to energize relay 160, thus completing the oil burner circuit and starting it in operation. At the beginning of furnace operation, said secondary circuit flows through safety switch 188, energizing heater coil 186. If, within a predetermined number of seconds from the beginning of operation, stack switch 178 has not been operated by the heat of the oil combustion products rising in stack pipe 8 to connect wire 176 directly with wire 182, heater coil will open switch 188, thus breaking the oil burner circuit. Safety switch 188 is retained in the open position by a latch 189, which must be manually released, thus preventing starting of the oil burner till the defects therein have been corrected. Transformer 150, relay 160, stack switch 178, and safety switch 188 are normally encased in a single housing and designated as the primary oil burner control 192, said control being disposed adjacent stack pipe 8 with bimetallic element 180 projecting into said stack pipe, as shown in Fig. 1.

The primary terminals of step-down transformer 194 are connected with wires 146 and 148 respectively by wires 196 and 198. One secondary terminal of said transformer is connected by wire 200 with an inside thermostat 202, which is in effect a switch adjustable to close whenever

the temperature in the building to be heated falls below the desired level. The other pole of said thermostat is connected by wires 204 and 206 with the armature of a double-throw relay 208. Said armature connects normally with a wire 210 connected to the coil of relay 174, and the other terminal of said coil is connected by wire 212, and wire 214 with a return wire 216 to the secondary of transformer 194. Thus whenever thermostat 202 is closed, calling for heat, the circuit to the coil of relay 174 will be completed through wire 200, thermostat 202, wires 204 and 206, relay 208, wire 210, the coil of relay 174, and wires 212, 214 and 216. Relay 174 will then close, actuating the oil burner circuit as previously described.

Wire 204 is connected by wire 218 with an outdoor thermostat 220, which is set to close at and above some temperature representing the period of peak gas load, and to open when the outside temperature falls below said predetermined level. It is contemplated that this thermostat should be set and sealed by the public utility authorities. The other pole of said thermostat is connected by wire 222 with one terminal of solenoid operated gas pilot valve 118, and return wire 216 is connected to the other terminal of said valve. Thus whenever thermostat 202 is closed to actuate the oil burner circuit as previously described, and the outdoor temperature is above the setting of thermostat 220, the circuit to pilot valve 118 will be completed through wire 200, thermostat 202, wires 204 and 218, thermostat 220, wire 222, valve 118 and wire 216. Pilot valve 118 is thus opened, permitting gas to flow through pilot tube 116 and to be ignited by the oil burner flame. Said pilot then ignites jet 134 of flame actuated switch 124. Said jet heats bimetallic element 126, and after a short time interval said bimetallic element will be actuated by said jet to close switch 130.

One pole of switch 130 is connected to wire 200 by wire 224, and the other pole of said switch is connected by wire 226 with the coil of relay 208, and thence to common return wire 216 by wire 214. Thus when switch 130 is closed by the action of jet 134, the circuit to the relay of coil 208 is completed through wires 200 and 224, switch 130, wire 226, relay 208, and wires 214 and 216. The armature of relay 208 thus breaks contact with wire 210, breaking the circuit to relay 174 and shutting off the oil burner, and establishes contact with wire 228, which is connected with main gas valve 114. The return wire 228 of said main gas valve is connected with common return wire 216. The circuit to the main gas valve is thus completed through wire 200, thermostat 202, wires 204 and 206, the armature of relay 208, wire 228, main valve 114, and wires 228 and 216. Main valve 114 is thereby opened, permitting gas to operate damper control 96, and to flow through header 86, nipples 88, nozzles 82, and burner tubes 74, where said gas is ignited by the pilot tube 116.

If for any reason the pilot has failed to ignite, the oil burner will continue to operate, since then flame actuated switch 130 will not be closed to energize relay 208 to interrupt the circuit to the oil burner. If, while the gas burner is in operation, the outdoor temperature should fall below the setting of thermostat 220, said thermostat will open. This breaks the circuit to gas pilot valve 118, and said valve will close, thus shutting off the gas to pilot tube 116 and jet 134 of flame switch mechanism 124. When bimetallic element 126 has cooled sufficiently, which requires only a few seconds, switch 130 will be opened, thereby breaking the circuit to the coil of relay 208. This re-

lay, thus de-energized, breaks the circuit to the main gas valve 114 and reestablishes the circuit to the coil of relay 174, and said relay closes the circuit to the oil burner as previously described. If, while the gas burner is in operation, the pressure in the gas supply line falls below a predetermined level, the flame at jet 134 of flame switch mechanism 124 will become too small to actuate bimetallic member 126, and switch 130 will open. This breaks the circuit to relay 208, which then operates to close the main gas valve and start the oil burner as described above. This cycle will also occur in case of total gas failure. In this instance the gas pilot will continue burning after the oil burner is lit, but this is not considered objectionable. If, after the oil burner has been put back in operation, the outside temperature should again rise above the level at which thermostat 220 is set, said thermostat will again close to initiate the gas lighting cycle previously described. Likewise, if the oil burner has been put in operation by low pressure or failure of the gas supply, and the pressure is again restored, jet 134 will again function to close switch 130, and relay 208 will function to shut off the oil burner and open the main gas valve.

As shown in Figs. 1 and 8, relays 174 and 208, and transformer 194, may be enclosed in a wall mounted housing 230. Line wires 146 and 148 from switch 152 pass to a junction box 232 through conduit 234. From said junction box, suitable connections are made to limit switch 154 through conduit 236, to primary oil burner control 192 through conduit 238, and to relay and transformer housing 230 through conduit 240. From said housing, connections are made to the oil burner through conduit 242, and to the gas control apparatus through conduit 244. A conduit 246 extends through floor partition 6 into the rooms to be heated for connection with inside thermostat 202, and a conduit 248 extends through outside wall 4 for connection with outside thermostat 220.

In the modified form of control system shown in Figs. 9 and 10, substantially similar results are obtained in a simpler manner using fewer controls. The pilot tube 116, pilot valve 118, flame actuated switch mechanism 124, and relays 174 and 208, which are present in the form shown in Figs. 1 to 8, are omitted. A pressure sensitive, diaphragm operated electric switch 250 is inserted in gas supply line 90 between main gas valve 114 and damper control 96, and an additional stack switch 252 is used, said stack switch being operable by a bimetallic element 254 adapted to be positioned in furnace stack pipe 8.

Referring to Fig. 9 for the wiring diagram of the modified control system, it will be noted that wires 146 and 148 are connected with main switch 152, limit switch 154, and the primary terminals of transformer 150 of primary burner control 192 just as in the preferred form. Said primary burner control is identical with the control used in the preferred form, however, the lead wires 172 and 182 of the secondary circuit of transformer 150 are connected directly to inside thermostat 202, and the line voltage lead wires 162 and 166 from said primary control are connected directly to the primary terminals of gas control transformer 194. Wire 162 is connected by wire 256 with one pole of pressure switch 250. The other pole of said switch is connected by wires 258 and 260 with oil burner motor 20 and the primary of ignition transformer 54. The return wires 262 and 264 of said motor and

transformer are connected with return wire 166. Thus when thermostat 202 closes to complete the circuit to the coil of relay 160, said relay closes and completes the circuit to the oil burner through wire 148, the armature of relay 160, wires 162 and 256, pressure switch 250, wires 258 and 260, motor 20, transformer 54, wires 262, and 264, and wires 166 and 146, and the oil burner will be placed in operation.

Pressure switch 250 is adapted to remain closed when the pressure in gas line 90 is below a predetermined level, and to open when said gas pressure reaches a predetermined higher level. For example, if the operating gas pressure is two ounces, switch 250 may be set to open when the gas pressure is $1\frac{1}{2}$ ounces or more, and to close when the gas pressure drops to $\frac{1}{2}$ ounce.

When the oil burner is placed in operation, the primary coil of transformer 194 is energized. Connected in series in the secondary circuit of said transformer are a wire 266, stack switch 252, wire 268, outside thermostat 220, wire 270, main gas valve 114, and wire 272. Stack switch 252 is adapted to remain open when the furnace is cold, and to close when the stack temperature rises to some predetermined higher temperature. Thus when the oil burner is first placed in operation by thermostat 202 and transformer 194 is energized, and when the outside temperature is high enough to close outside thermostat 220, main gas valve 114 can not open immediately since stack switch 252 is open. After the oil burner has been in operation a few seconds, the stack temperature will become sufficiently high to close the stack switch 252, and the circuit to main gas valve 114 will be completed thereby. Said valve, thus opened, allows gas to flow through pipe 90 to operate damper control 96 and to pass to burner tubes 74, where said gas will be ignited by the oil burner. When the gas pressure reaches the level required to open pressure switch 250, said switch will open, thus breaking the circuit to the oil burner. Valve 114 is solenoid operated and hence quick acting, while switch 250 is diaphragm operated and hence inherently slow operating. In this manner a sufficient time lapses between the opening of valve 114 and the opening of switch 250 to insure that the gas burner will be ignited before the oil burner is turned off. Should the outdoor temperature fall below the setting of the thermostat 220, said thermostat will open, thus breaking the circuit to gas valve 114 and closing said valve. Switch 250 will then close the circuit to the oil burner, setting said oil burner in operation. Thus the gas burner can operate only when the outside temperature is above a predetermined level, as determined by thermostat 220.

However, if, while the gas burners are operating, the pressure in the gas line at any time falls below the closing pressure of switch 250, or if the gas supply fails completely, switch 250 will immediately close to set the oil burner in operation.

If the gas pressure is adequate, but the gas for any reason fails to ignite when valve 114 opens, bimetallic element 254 of stack switch 252 will immediately begin to cool, and within a few seconds opens said switch, thereby breaking the circuit to valve 114 and closing said valve. Switch 250 will then be closed, starting the oil burner in operation. Stack switch 252 will normally open before stack switch 178 of the primary burner control 192 functions to throw safety switch 188 into the circuit and said safety switch

normally remains closed. The time required for heating coil 186 to actuate switch 188 is sufficient for this purpose. However, if after stack switch 252 opens, thereby closing valve 114 and closing switch 250 to start the oil burner, the oil burner itself should fail to ignite, safety switch 188 would have time to open, thereby shutting down the entire system until the trouble is corrected.

While I have disclosed specific embodiments of my invention, it is apparent that many minor variations of construction and operation could be made without departing from the spirit of the invention, and it is therefore desired to be limited only by the scope of the appended claims.

What I claim as new and desire to protect by Letters Patent is:

1. A combination gas and oil burner and control system therefor comprising an oil burner, a gas burner, means for supplying fuel oil and gas respectively to said burners, automatic means responsive to the temperature of the space heated by said burners for setting said oil burner in operation to produce flame whenever heat is required, a gas valve controlling said supply means for said gas burner, means operable by the heat of combustion of said oil burner for opening said valve to supply gas to said gas burner, said gas burner being positioned to deliver gas adjacent the delivery end of said oil burner so that said gas is ignited by said oil burner flame, automatic means responsive to the outdoor temperature for rendering said valve opening means operable only when the outside atmosphere is above a predetermined temperature, and automatic time delay means operable by the pressure of the gas thus supplied to said gas burner to shut down said oil burner.

2. A combination gas and oil burner and control system therefor comprising an oil burner, a gas burner, means for supplying fuel oil and gas respectively to said burners, automatic means responsive to the temperature of the space heated by said burners for setting said oil burner in operation to produce flame whenever heat is required, a quick-operating gas valve controlling said supply means for said gas burner, means operable by the heat of combustion of said oil burner for opening said valve to supply gas to said gas burner, said gas burner being positioned to deliver gas adjacent the delivery end of said oil burner so that said gas is ignited by said oil burner flame, a relatively slow-operating pressure sensitive means operable by the gas thus supplied to said gas burner for shutting down said oil burner, and automatic means responsive to the outdoor temperature for rendering said valve operating means operable only when said outdoor temperature is above a predetermined level.

3. A combination gas and oil burner and control system therefor comprising an oil burner, a gas burner, means for supplying fuel oil and gas respectively to said burners, automatic means responsive to the temperature of the space heated by said burners for setting said oil burner in operation to produce flame whenever heat is required, a gas valve controlling said supply means for said gas burner, means operable by the heat of combustion of said oil burner for opening said valve to supply gas to said gas burner, said gas burner being positioned to deliver gas adjacent the delivery end of said oil burner so that said gas is ignited by said oil burner flame, automatic means responsive to the outdoor temperature and operable to render said valve opening means operable only when said outside temperature is above a

predetermined level, and pressure sensitive time delay means operable by the pressure of the gas thus supplied to said gas burner to shut down said oil burner whenever said gas pressure is above a predetermined high level, and to set said oil burner in operation whenever said gas pressure falls below a predetermined lower level.

4. A combination gas and oil burner and control system therefor comprising an oil burner, a gas burner, means for supplying fuel oil and gas respectively to said burners, automatic electrical means controlled by an indoor thermostat disposed in the space heated by said burners for setting said oil burner in operation to produce flame whenever heat is required, an electrically operated quick-opening gas valve whereby gas is supplied to said gas burner, automatic electrical means including a thermostatic stack switch operable by the heat of combustion of said oil burner to open said gas valve, said gas burner being positioned to deliver gas adjacent the delivery end of said oil burner so that gas supplied to said gas burner is ignited by said oil burner flame, an outdoor thermostat connected in series with said gas valve and said stack switch and adapted to render said valve opening means operable only when the outdoor temperature is above a predetermined level, and to close said gas valve whenever the outside temperature falls below said predetermined level, and a pressure sensitive time delay switch disposed between said gas valve and said gas burner, said pressure sensitive switch being adapted to break the circuit to said oil burner whenever the gas pressure is above a predetermined high level, and to reestablish the circuit to said oil burner whenever said gas pressure falls below a predetermined level.

5. A combination gas and oil burner and control system therefor comprising an oil burner, a gas burner, means for supplying fuel oil and gas respectively to said burners, a main valve controlling said gas supply, a gas pilot for said gas burner, a valve controlling the gas supply to said pilot, automatic means responsive to the temperature of the space heated by said burners for setting said oil burner in operation to produce flame whenever heat is required, automatic means responsive to the outside temperature for opening said pilot valve whenever said outside temperature is above a predetermined level and said oil burner is in operation, said gas pilot being positioned to deliver gas adjacent the delivery end of said oil burner whereby gas supplied to said pilot is ignited by said oil burner flame, and means operable by the flame of said pilot for shutting down said oil burner and opening said main valve, whereby gas is supplied to said gas burner and ignited by said pilot.

6. A combination gas and oil burner and control system therefor comprising an oil burner, a gas burner, means for supplying fuel oil and gas respectively to said burners, a main valve controlling said gas supply, a gas pilot for said gas burner, a valve controlling the gas supply to said pilot, automatic means responsive to the temperature of the space heated by said burners for setting said oil burner in operation to produce flame whenever heat is required, automatic means responsive to the outside temperature for opening said pilot valve whenever said outside temperature is above a predetermined level and said oil burner is in operation, said gas pilot being positioned to deliver gas adjacent the delivery end of said oil burner whereby gas supplied to said pilot is ignited by said oil burner flame, and

to close said pilot valve whenever said outside temperature falls below said predetermined level, and means actuated by the flame of said pilot for shutting down said oil burner and opening said main valve to supply gas to said gas burner, said flame actuated means being dependent upon the continued supply of gas at a predetermined pressure to said pilot, whereby when said pilot gas falls below said predetermined pressure, said main valve will be closed and said oil burner set in operation.

7. A combination gas and oil burner and control system therefor comprising an oil burner, a gas burner, means for supplying fuel oil and gas respectively to said burners, a main valve controlling said gas supply, a gas pilot for said gas burner, a valve controlling the gas supply to said pilot, automatic means responsive to the temperature of the space heated by said burners for setting said oil burner in operation to produce flame whenever heat is required, automatic means responsive to the outside temperature for opening said pilot valve whenever said outside temperature is above a predetermined level and said oil burner is in operation, said gas pilot being positioned to deliver gas adjacent the delivery end of said oil burner whereby gas supplied to said pilot is ignited by said oil burner flame, and to close said pilot valve whenever said outside temperature falls below said predetermined level, an auxiliary gas jet adapted to receive gas through said pilot valve and positioned so that gas delivered thereto is ignited by the primary pilot flame, and thermostatic means operable by the heat of said auxiliary jet to shut down said oil burner and open said main valve, whereby gas is supplied to said gas burner and ignited by said pilot, said thermostatic means being operable whenever the flame of said auxiliary jet is extinguished or reduced by failure of the gas supply or reduction of the gas supply below a predetermined pressure to close said main gas valve and set said oil burner in operation.

8. A combination gas and oil burner and control system therefor comprising an oil burner, a gas burner, means for supplying fuel oil and gas respectively to said burners, means controlled by a thermostat disposed in the space to which heat is supplied by said burners for automatically setting said oil burner in operation to produce an oil flame whenever heat is required, means rendered operable by the heat of combustion of said oil burner for shutting down said oil burner and supplying gas to said gas burner, said last named means including a time delay means whereby said oil burner is continued in operation for a short time after the gas supply is initiated, said gas burner being positioned to deliver gas adjacent the delivery end of said oil burner whereby said gas is ignited by the oil flame, and automatic means responsive to the temperature of the outdoor atmosphere and operable to render said last named means inoperative to shut down said oil burner and inoperative to supply gas to said burner when said outdoor atmosphere falls below a predetermined temperature.

9. A combination gas and oil burner and con-

trol system therefor comprising an oil burner, a gas burner, means for supplying fuel oil and gas respectively to said burners, means controlled by a thermostat disposed in the space to which heat is supplied by said burners for automatically setting said oil burner in operation to produce an oil flame whenever heat is required, means rendered operable by the heat of combustion of said oil burner for shutting down said oil burner and supplying gas to said gas burner, said last named means including a time delay means whereby said oil burner is continued in operation for a short time after the gas supply is initiated, said gas burner being positioned to deliver gas adjacent the delivery end of said oil burner whereby said gas is ignited by the oil flame, and automatic means responsive to the pressure of the fuel gas supply and operable to render said last named means inoperative to shut down said oil burner and inoperative to supply gas to said burner when said pressure falls below a predetermined level.

10. A combination gas and oil burner and control system therefor comprising an oil burner, a gas burner, means for supplying fuel oil and gas respectively to said burners, means controlled by a thermostat disposed in the space to which heat is supplied by said burners for automatically setting said oil burner in operation to produce an oil flame whenever heat is required, means rendered operable by the heat of combustion of said oil burner for shutting down said oil burner and supplying gas to said gas burner, said last named means including a time delay means whereby said oil burner is continued in operation for a short time after the gas supply is initiated, said gas burner being positioned to deliver gas adjacent the delivery end of said oil burner whereby said gas is ignited by the oil flame, and automatic means responsive to the temperature of the outdoor atmosphere and to the pressure of the fuel gas supply and operative to render said last named means inoperative to shut down said oil burner and inoperative to supply gas to said burner whenever either said outdoor temperature or said gas pressure falls below a predetermined level.
